CLAIM

The ornamental design for an organizer drawer for audio cassettes, discs, or the like to be used in an automobile, as shown and described.

DESCRIPTION

FIG. 1 is a perspective view of an organizer drawer for audio cassettes, discs, or the like to be used in an automobile showing our new design;

FIG. 2 is a left side elevational view thereof, the right side being a mirror image;

FIG. 3 is a front elevational view thereof, the rear being plain and unornamented;

FIG. 4 is a perspective view of an alternate embodiment of the design shown in **FIG. 1**;

FIG. 5 is a left side elevational view of **FIG. 4**;

FIG. 6 is a front elevational view of **FIG. 4**; and,

FIG. 7 is a bottom plan view of **FIG. 4**.
